J. D. PEDERSEN.

FIREARM.

APPLICATION FILED DEC. 13, 1919.

1,391,498.

Patented Sept. 20, 1921.

Inventor:
John D. Pedersen,
By his Atty, F. M. Richards.

UNITED STATES PATENT OFFICE.

JOHN D. PEDERSEN, OF JACKSON, WYOMING.

FIREARM.

1,391,498.

Specification of Letters Patent. Patented Sept. 20, 1921.

Application filed December 13, 1919. Serial No. 344,677.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to fire-control mechanisms for use in auto-loading small-arms, and more particularly to 10 that class of such mechanisms which is illustrated and described in my Patent No. 1,348,733, dated August 3, 1920, filed July 17, 1919. A principal object of the present 15 improvements is to provide an organization of fire-control mechanism in which the operation of certain of the coacting members shall be more simple in character, and in which an improved safety-grip control shall 20 be coactive with firing-train and its associated devices; further objects and advantages are hereinafter explained in the course of the description.

Certain of the principal features of my 25 present improvements are shown in Figs. 80, 81, 82 and 83 of said patent, in which these features are described as a modification that is within the scope of claims therein broadly defined. In this present application, 30 however, certain of the details of the mechanism, shown in said views of said prior application, in a more simple form, are further improved in construction and arrangement, and are also employed in new combinations not disclosed in said prior application.

In the accompanying drawings forming a part of this specification, Figure 1, is a side view, and Fig. 2 an end view (as seen 40 from the right-hand in Fig. 1), of one kind of auto-loading pistols to which my present improvements are applicable; these two views correspond, respectively, with Figs. 1 and 2 of said patent.

Fig. 3, is a side view, on an enlarged scale, of the rearward portion of the pistol, the forward end being omitted, and the frame 45 shown broken away for illustrating the interior mechanism; this view corresponds, in large part, with Fig. 3 of said patent, in which the various operable parts not restricted to the present invention, are more 50 fully illustrated and described.

Fig. 4, is a horizontal section, in plan view, 55 of the rear portion of the pistol on the line 4-4 of Fig. 3, with the sliding breechac-

tion of the pistol removed, and showing parts of my fire control mechanism.

Fig. 5, is a side view of a portion of the rear of the pistol, showing parts of my fire 60 control mechanism, the hammer being in firing position, the sliding breechaction of the pistol locked by the slideable member or controller, the hammer and sear locked, the trigger member out of contact with the dis- 65 connector located between it and the sear, and the sear in contact with said disconnector and out of contact with said controller.

Fig. 5^a, is an end view in vertical section on the line 5^a-5^a, of Fig. 3, of the rear portion of the pistol showing details of my fire 70 control mechanism.

Fig. 6, is a side view of the rear end portion of the pistol showing parts of my fire 75 control mechanism, the hammer being in firing position, the sliding breechaction locked by said controller, the hammer and sear locked, the trigger member, preparatory to firing, in contact with said disconnector and out of contact with said controller. 80

Fig. 7, is a side view of a portion of the rear end of the pistol showing parts of my fire control mechanism, the hammer being in fired position, the breechaction unlocked from the slideable controller, the hammer and sear unlocked, the trigger-member, after firing, in contact with said disconnector, and the sear out of contact with said disconnector and in contact with said controller. 85

Fig. 8, is a side view of the rear portion 90 of the pistol showing the breechaction moved rearwardly to cock the pistol and unlock from the controller, the hammer being in course of movement to firing position and not yet positively engaged with the 95 sear, the trigger-member being in contact with said disconnector prior to forward movement of the trigger-member, and the sear in contact with said disconnector and out of contact with said controller. 100

Similar reference characters or numerals refer to similar parts throughout the several views.

My fire control mechanism comprises, together with the various parts hereinafter 105 described, a firing member or hammer H, movable to firing position and to fired position. The firing member or hammer in the present embodiment of my invention is moved to firing or cocked position by engagement therewith of a roller 3^c, on the sliding breechaction or main slide C of the 110

pistol, as the sliding breechaction or main-slide C is moved rearwardly when the pistol is discharged. The firing member or hammer H is provided with a firing-notch or 5 cock-notch 8ⁱ and an eccentric cam face 8^k.

The sear member S is provided with a locking shoulder 17^b for engaging the cock-notch 8ⁱ, and with a face 17ⁿ, for engaging the eccentric cam face 8^k of the firing member or hammer H, and with arms 17^t, only 10 one of which arms is shown in the views, for engaging the slidable member or controller N. The sear member S is provided with a downwardly extending portion which affords a face 17^e for engagement therewith of a contactor, and with an end 17^d which engages a disconnector, such contactor and such disconnector being hereinafter described.

The slidable member or controller N is 20 movable upwardly and downwardly between slide-faces 15 and 16, formed in the frame and grip-stock of the pistol. The slidable member or controller N has at its upper end a projecting portion or end 14^d which is engageable with the sliding breech action of the pistol when the slidable member or controller N is in upward position, to prevent rearward movement of the sliding breech action.

25 The slidable member or controller N is provided with a shoulder 14^p having upper engaging surfaces 14^e with which the arms 17^b of the sear member S are engageable, and at its lower end is provided with a recess 17 to receive the upper end of the actuator 35 14^m, hereinafter described. The slidable member or controller N has at its lower end end-faces or bottom-faces 14^t.

The actuator 14^m, the purpose of which is 40 to move the slidable member or controller N upwardly, comprises a plug or nose-piece 18 having a stem 19, which is seated at its lower end in a bracket formed in the grip-stock of the pistol, the plug or nose-piece 18 being 45 movable or slidable upwardly and downwardly in the recess 17 of the slidable member or controller N, and in a recessed or bored member 17', formed in the grip-stock of the pistol, the plug or nose-piece 18 never 50 being entirely retractable from the recess 17, and by its engagement with said recess 17, and with said recessed or bored member 17', providing a means for preventing inward shifting of the lower end of the slidable member or controller N. But I do not restrict myself to this means for preventing such inward shifting, as any suitable means 55 for this purpose may be used.

The disconnector k is pivotally movable 60 and comprises a base or block 19, which is pivotally attached to the slidable member or controller N, and a stem 20. The stem 20 has an outer or front face 21 and an upper end-face 22, and an inner or rear face 23. 65 The end of the trigger member F is engage-

able with said front face 21 when the firing member or hammer H is in firing position, and is engageable with said end-face 22, when the firing member or hammer H is in fired position, and the end 17^d of the sear member S is engageable with said rear face 23 when the firing member or hammer is in firing position. The stem 20 thus lies between the trigger member F and the sear member S.

70 The trigger member F is movable forwardly by means not shown, and by pull thereon is movable rearwardly. The trigger member F is provided with an end 6^s consisting of an end-face and an adjacent curved face, the end-face being intended to engage the outer face 21 of the stem of the disconnector k when the firing member or hammer H is in firing position and the sliding member or controller N is in upward position, 80 and the adjacent curved face is intended to engage, or ride upon, the upper end-face 22 of said disconnector when the firing member or hammer H is in fired position and the disconnector k has moved downwardly with 90 the downward movement of the slidable member or controller N.

95 My fire control mechanism is provided with a grip-safety portion or device, generally denoted by G, which comprises a grip-operable member or grip-safety member G'. The grip-safety member G' is hand compressible or yieldable, and is pivoted to the grip-stock of the pistol by means of a pivot-pin g, preferably in the manner described 100 and set forth in my said patent.

105 The grip-safety member G' closes the slot or space 2^s formed in the grip-stock of the pistol and which slot or space is of use in assembling the details of my invention.

110 The top portion of the grip-safety member G' is slotted out to furnish clearance for the firing member or hammer H and the sear member S, leaving a pair of side walls 7^s which are extended to provide a pair of locking-prongs 7^b. When the end G² of the grip-safety member G' is in rearward position, or position of safety, the locking-prongs or lever-arms 7^b are immediately below the end-faces or bottom-faces 14^t of the slidable member or controller N which is thereby locked against downward movement. The contactor, 24, is carried by the grip-safety member and is in engagement with the sear member S whether the grip-safety member 115 is in position of safety or compressed. The contactor 24, consists of a point or nose-piece 25, which is moved or pushed outwardly from a recessed member or case by a spring 26 contained in said recessed member or case, the tendency of the spring 26 being to retain the point or nose-piece 25, in contact or engagement with the face 17^e of the sear member, and thereby hold the lower end 17^d of the sear member in contact or engagement 120 125 130

with the inner or rear face 23 of the disconnector *k* when the firing member or hammer *H* is in firing position and the grip-safety member *G'* is in position of safety.

5 The firing spring 8^e, or spring for actuating the firing member or hammer *H*, is seated in the grip-stock adjacent to the lower end of the grip-safety member *G'*, preferably in the manner described in my

10 last above-mentioned co-pending application, the pressure of the spring 8^e being upward. A cupped member or cupped plunger 8^c, which is movable or slides between a side-face formed in the grip-stock of the 15 pistol and the grip-safety member *G'*, affords an abutment for the spring 8^e, the movable member or plunger 8^c thus engaging in its movement the grip-safety member *G'*.

20 A rod 8^b is pivotally attached at its upper end to the firing member or hammer *H*, and has a rounded lower end which is seated in the cupped portion of the movable member or plunger 8^c.

25 In operation, Figs. 3 and 5, the sliding breech-action of the pistol being in forward position, is locked in this position by engagement therewith of the slidable member or controller *N* which is held in upward or 30 locking position by the locking prongs 7^b of the grip-safety member *G'*, the slidable member having been moved upwardly by the actuator 14^m.

The firing member or hammer *H* having 35 been moved to firing position, is locked in this position by the sear member *S*, the lower end of which is in contact or engagement with the disconnector *k*, being held in this position by the contactor 24. The trigger member *F* is in contact with disconnector *k* preparatory to rearward pull on the trigger member, and the grip-safety member *G'* is in rearward position, or position of safety. The slidable member or controller *N* when in upward position thus locks 45 the sliding breech action of the pistol and locks the sear member and firing member or hammer in firing position.

Grip-compression of the grip-safety member *G'*, Figs. 7 and 8, releases the locking prongs 7^b thereof from engagement with the slidable member or controller *N* to permit downward movement thereof. Pull on the trigger member *F* moves the disconnector *k* inwardly and thereby moves the sear member *S*, to release the firing member or hammer *H* for movement to fired position by the spring 8^e, the arms 17^t of the sear member engaging or bearing down upon the 55 upper surfaces of the shoulder 14^p of the slidable member or controller *N*, as the firing member or hammer *H* is moved to fired position, to move the slidable member or controller downwardly and out of locking 60 position. Pull on the trigger member *F* also

causes this end of the trigger member to engage or ride up on the upper end of the disconnector *k* while the curved face of the end of the trigger member *F* engages the adjacent side face of the disconnector *k* and 70 assists in overcoming the pressure of the spring of the actuator 14^m to afford downward movement of the slidable member or controller *N*.

Release of grip-compression of the grip-safety member *G'* returns the grip-safety member *G'* to position of safety and the various other parts of my invention to the position shown in Figs. 3 and 5, and above described.

Having thus described my invention, I claim:

1. In a firearm, in combination, a sliding breech-action of said firearm, a frame of said firearm, a firing member movable to firing position and to fired position, sear means engageable with said firing member, slidable means engageable with said sliding breechaction, and provided with disconnecting means, means for moving said slidable 85 means and disconnecting means to position for locking said sliding breechaction, and locking said sear means and firing member in firing position, a grip-compressible member engageable, when in position of safety, 90 with said frame and engageable with said slidable means to block said slidable means and disconnecting means in said locking position, and releasable by grip-compression from both said engagements, spring means 100 for moving said firing member to fired position, and trigger-means engageable with disconnecting means for moving said sear means, when said grip-compressible member is grip-compressed, to release said firing member for movement to fired position and thereby to move said sear means for moving said slidable means and disconnecting means from said locking position.

2. In a firearm, in combination, a frame of said firearm, a firing member movable to firing position and to fired position, sear means engageable with said firing member, slidable means provided with disconnecting means, means for moving said slidable means and disconnecting means to position for locking said sear means and firing member in firing position, means for guiding said slidable means in its sliding movement, a grip-operable member engageable, when in position of safety, with said frame and with said slidable means to block said slidable means and disconnecting means in said locking position, and releasable by grip-compression from both said engagements, spring means 115 for moving said firing member to fired position, and affording grip-compression of said grip-operable member, and for returning said member to engagement with said frame after grip-compression, and trigger 120 125 130

means engageable with said disconnecting means for moving said sear means, when said grip-operable member is grip-compressed, to release said firing member for movement to 5 fired position and thereby to move said sear means for moving said slidable means and disconnecting means from said locking position.

3. In a firearm, in combination, a sliding breechaction of said firearm, a frame of said firearm, a firing member movable to firing position and to fired position, sear means engageable with said firing member, slidable means engageable with said sliding breech- 10 action and provided with disconnecting means, means for moving said slidable means to position for locking said sear means and firing member in firing position, means for guiding said slidable means in its sliding 15 movement, a grip-operable member engageable, when in position of safety, with said frame and with said slidable means to block said slidable means and disconnecting means in said locking position, and releasable by 20 grip-compression from both said engagements, spring means for moving said firing member to fired position, and affording grip-compression of said grip-operable member, and for returning said grip-operable member 25 to engagement with said frame after grip-compression, and trigger means engageable with said disconnecting means for moving said sear means, when said grip-operable member is grip-compressed, to release said 30 firing member for movement to fired position and thereby to move said sear means for moving said slidable means and disconnecting means from said locking position.

4. In a firearm, in combination, a frame of 40 said firearm, a firing member movable to firing position and to fired position, a sear member engageable with said firing member, a slidable member provided with disconnecting means, means for moving said 45 slidable member and disconnecting means to position for locking said sear member and firing member in firing position, means for guiding said slidable member in its sliding movement, means for preventing shifting 50 movement of said slidable member, a grip-operable member engageable, when in position of safety, with said frame and with said slidable member to block said slidable member and disconnecting means in said locking 55 position, and releasable by grip-compression from both said engagements. spring means for moving said firing member to fired position, and permitting grip-compression of said grip-operable member, and for returning said member to engagement with said frame after grip-compression, and trigger means engageable with said disconnecting means for moving said sear member, when said grip-operable member is grip-compressed, to release said firing member for movement to 60 fired position and thereby to move said sear member for moving said slidable member and disconnecting means from said locking position.

65

movement to fired position and thereby to move said sear member for moving said slid- 70 able member and disconnecting means from said locking position.

5. In a firearm, in combination, a sliding breechaction of said firearm, a frame of said firearm, a firing member movable to firing position and to fired position; a sear member engageable with said firing member, a slid- 75 able member engageable with said slid- ing breechaction and provided with disconnecting means, means for moving said slid- able member and disconnecting means to position for locking said sliding breech- action and locking said sear member and 80 firing member in firing position, means for guiding said slidable member in its sliding movement, means for preventing shifting movement of said slidable member, a grip- operable member engageable, when in posi- 85 tion of safety, with said frame and with said slidable member to block said slidable member and disconnecting means in said locking position, and releasable by grip- compression from both said engagements, 90 spring means for moving said firing member to fired position, and permitting grip- compression of said grip-operable member, and for returning said grip-operable member to engagement with said frame after 95 grip-compression, and trigger means en- gageable with said disconnecting means for moving said sear member, when said grip- operable member is grip-compressed, to re- 100 lease said firing member for movement to fired position and thereby to move said sear member for moving said slidable member and disconnecting means from said locking position.

6. In a firearm, in combination, a frame 105 of said firearm comprising a grip-stock, a firing member movable to firing position and to fired position, a sear member engageable with said firing member, a slidable controller provided with a disconnector, said 110 disconnector being engageable with said sear member, means for guiding said slid- able controller in its sliding movement, an actuator for moving said slidable controller and disconnector upwardly to lock said sear member and firing member in firing position, means engaging said actuator for pre- 115 venting shifting of said slidable controller, a grip-operable member pivotally attached to said grip-stock and engageable with said frame and with said slidable controller, when in position of safety, to prevent down- 120 ward movement of the slidable controller and disconnector, and releasable by grip- compression from both said engagements, 125 means for retaining said sear member in engagement with said disconnector, spring means for moving said firing member to fired position, and permitting grip-compression of said grip-operable member, and for 130

- returning said grip-operable member to engagement with said frame after grip-compression, and a trigger member engageable with said disconnector for moving said sear member, when said grip-operable member is grip-compressed, to release said firing member for movement to fired position and thereby to move said sear member for moving said slidable member and disconnector, 10 downwardly.
7. In a firearm, in combination, a sliding breechaction of said firearm, a frame of said firearm comprising a grip-stock, a firing hammer movable to firing position and to fired position, a sear member engageable with said firing hammer, a slidable controller engageable with said sliding breechaction and provided with a disconnector, said disconnector being engageable with 15 said sear member, means for guiding said slidable controller in its sliding movement, an actuator for moving said slidable controller and disconnector upwardly to lock said sliding breechaction and lock said sear member and firing hammer in firing position, means engaging said actuator for preventing shifting of said slidable controller, a grip-operable member pivotally attached to said grip-stock and engageable with said 20 frame and with said slidable controller, when in position of safety, to prevent downward movement of the slidable controller and disconnector, and releasable by grip-compression from both said engagements, 25 means for retaining said sear member in engagement with said disconnector, spring means for moving said firing hammer to fired position, and permitting grip-compression of said grip-operable member, and 30 for returning said grip-operable member to engagement with said frame after grip-compression, and a trigger member engageable with said disconnector for moving said sear member, when said grip-operable member is grip-compressed, to release said firing hammer for movement to fired position and thereby to move said sear member to move said slidable controller and disconnector 35 downwardly.
- 50 8. In a firearm, in combination, a frame of said firearm comprising a grip-stock, a firing hammer movable to firing position and to fired position and provided with a cock-notch and an eccentric cam face, a sear member provided with a locking shoulder for engaging said cock-notch and a face for engaging said eccentric cam face, and provided with an arm and an extending lower end, a 45 slidable controller provided with means for engaging said sliding breechaction, and provided with a shoulder having upper surfaces for engagement therewith of said arm of the sear member for downward movement of the controller by said sear member, and provided with a slot for receiving a trigger member, and provided with a recess for receiving an actuator, and provided with bottom end-faces, means for guiding said 55 slid able controller in its sliding movement, a disconnector pivotally attached to said slid able controller and provided with a front face and an end-face, and provided with a rear-face for engaging said extending end of the sear member, an actuator comprising a plug slidably engaging said recess of the slid able controller, and a spring for actuating said plug to move the slid able controller upwardly, a recessed member secured to said 60 65 70 75 80 85 90 95 100 105 110 115 120 125 130

- grip-stock, said plug engaging said recess of the slidable controller and said recessed member to prevent shifting of the lower end of the controller, a grip-safety member pivotally attached at its lower end to said grip-stock, and engageable at its upper end with said frame, and provided with locking-prongs for engaging said bottom faces of the slidable controller when in position of safety, and releasable by grip-compression from both said engagements, a spring actuated contactor carried by said grip-safety member and engaging the rear face of said extending end of the sear member, a rod pivotally attached at the upper end to said firing hammer, a spring seated in said grip-stock, a movable member operative between said rod and said spring and engaging said grip-safety member, providing a seat for the lower end of said rod and an abutment for said spring, and a trigger member provided with an end-face and an adjacent curved face for engaging said front-face and end-face of said disconnector.
- 25- 10. In a firearm, in combination, a firing member movable to firing position and to fired position, sear means engageable with said firing member, trigger means, slidable means provided with disconnecting means and movable to lock said sear means and firing member in firing position, and releasable means for retaining said slidable means and disconnecting means in said locking position; said trigger means being engageable with said disconnecting means for moving said sear means, when said retaining means is released, to release said firing member for movement to fired position and thereby to move said sear means for moving said
- 30 40 slidable means and disconnecting means from said locking position.
11. In a firearm, in combination, a sliding breech action of said firearm, a firing member movable to firing position and to fired position, sear means engageable with said firing member, trigger means, slidable means engageable with said sliding breech action and provided with disconnecting means, and movable to lock said sliding breech action, and lock said sear means and firing member in firing position, and releasable means for retaining said slidable means and disconnecting means in said locking position; said trigger means being engageable with said disconnecting means for moving said sear means, when said retaining means is released, to release said firing member for movement to fired position and thereby to move said sear means for moving said
- 35 45 50 55 60 slidable means and disconnecting means from said locking position.
12. In a firearm, in combination, a firing member movable to firing position and to fired position, sear means engageable with said firing member, trigger means, slidable means engageable with said sliding breech action and provided with disconnecting means, and movable to lock said sliding breech action, and lock said sear means and firing member in firing position, and releasable means for retaining said slidable means and disconnecting means in said locking position; said trigger means being engageable with said disconnecting means for moving said sear means, when said retaining means is released, to release said firing member for movement to fired position and thereby to move said sear means for moving said

means provided with disconnecting means and movable to lock said sear means and firing member in firing position, and a grip-compressible member for retaining said slidable means and disconnecting means in said locking position, and releasable by grip-compression; said trigger means being engageable with said disconnecting means for moving said sear means, when said grip-compressible member is grip-compressed, to release said firing member for movement to fired position and thereby to move said sear means for moving said slidable means and disconnecting means from said locking position.

13. In a firearm, in combination, a sliding breech-action of said firearm, a firing member movable to firing position and to fired position, sear means engageable with said firing member, trigger means, slidable means engageable with said sliding breech-action and provided with disconnecting means, and movable to lock said sliding breechaction, and lock said sear means and firing member in firing position, and a grip-compressible member for retaining said slidable means and disconnecting means in said locking position, and releasable by grip-compression; said trigger means being engageable with said disconnecting means for moving said sear means, when said grip-compressible member is grip-compressed to release said firing member for movement to fired position and thereby to move said sear means for moving said slid- 10 able means and disconnecting means from said locking position.

14. In a firearm, in combination, a firing member movable to firing position and to fired position, sear means engageable with said firing member, trigger means, slidable means provided with disconnecting means, means for moving said slidable means and disconnecting means upwardly to lock said sear means and firing member in firing position, and a grip-compressible member for retaining said slidable means and disconnecting means in said upward locking position, and releasable by grip-compression; said trigger means being engageable with said disconnecting means for moving said sear means, when said grip-compressible member is grip-compressed, to release said firing member for movement to fired position and thereby to move said sear means for moving said slidable means and disconnecting means downwardly from said locking position.

15. In a firearm, in combination, a sliding breechaction of said firearm, a firing member movable to firing position and to fired position, sear means engageable with said firing member, trigger means, slidable means engageable with said sliding breechaction and provided with disconnecting means, 120

means for moving said slidable means and disconnecting means upwardly to lock said sliding breechaction, and lock said sear means and firing member in firing position, 5 and a grip-compressible member for retaining said slidable means and disconnecting means in said upward locking position, and releasable by grip-compression; said trigger-means being engageable with said 10 connecting means to move said sear means,

when said grip-operable member is grip-compressed, to release said firing member for movement to fired position and thereby to move said sear means for moving said slidable means and disconnecting means 15 downwardly from said locking position.

JOHN D. PEDERSEN.
